UNITED STATES PATENT OFFICE.

MARSHAL G. ROBERTS, OF DETROIT, MICHIGAN.

DESIGN FOR A WINDOW FOR AN AUTOMOBILE-CURTAIN.

382.

Specification for Design.

Patented Oct. 5, 1920.

Application filed January 14, 1920. Serial No. 351,491. Term of patent 3½ years.

To all whom it may concern:

Be it known that I, MARSHAL G. ROBERTS, a citizen of the United States, residing at Detroit, in the county of Wayne and State of Michigan, have invented a new, original, and ornamental Design for Windows for Automobile-Curtains, of which the following is a specification, reference being had to the accompanying drawing, forming a part thereof, of which—

Figure 1 is a perspective of a portion of an automobile body showing two of my novel curtain windows in position in the back curtain thereof.

Fig. 2 is an elevation of a fragment of an automobile curtain provided with a window of my design.

In the drawing, let *a* represent the fabric curtain of an automobile top; *b* the window pane of my new design and *c* the metal frame following the outline of the window pane and in which the window is seated.

I claim:

The ornamental design of a window for an automobile curtain as shown in the drawing.

MARSHAL G. ROBERTS.
